(57) **CLAIM**

The ornamental design for a curtain ring with decorative balls, as shown and described.

DESCRIPTION

FIG. 1 is a front elevational view of a curtain ring with decorative balls showing my new design;

FIG. 2 is a side elevational view thereof;

FIG. 3 is a top plan view thereof;

FIG. 4 is a front, right perspective view thereof;

FIG. 5 is a front elevational view of a second embodiment of a curtain ring with decorative balls showing my new design;

FIG. 6 is a front elevational view of a third embodiment of a curtain ring with decorative balls showing my new design;

FIG. 7 is a front elevational view of a fourth embodiment of a curtain ring with decorative balls showing my new design;

FIG. 8 is a front elevational view of a fifth embodiment of a curtain ring with decorative balls showing my new design;

FIG. 9 is a front elevational view of a sixth embodiment of a curtain ring with decorative balls showing my new design with the ring fully closed;

FIG. 10 is a front elevational view of a seventh embodiment of a curtain ring with decorative balls showing my new design with the ring fully closed;

FIG. 11 is a front elevational view of an eighth embodiment of a curtain ring with decorative balls showing my new design with the ring fully closed;

FIG. 12 is a front elevational view of a ninth embodiment of a curtain ring with decorative balls showing my new design with the ring fully closed; and,

FIG. 13 is a front elevational view of a tenth embodiment of a curtain ring with decorative balls showing my new design with the ring fully closed.

It is understood that the undisclosed portions of embodiments **2-10** are the same as embodiment **1**.
